UNITED STATES PATENT OFFICE.

RUSSEL G. WOODWARD, OF CHICAGO, ILLINOIS, ASSIGNOR TO UNION SPECIAL MACHINE COMPANY, OF CHICAGO, ILLINOIS, A CORPORATION OF ILLINOIS.

SEWING-MACHINE.

1,118,092.

Specification of Letters Patent. Patented Nov. 24, 1914.

Application filed August 6, 1909. Serial No. 511,596.

To all whom it may concern:

Be it known that I, RUSSEL G. WOODWARD, a citizen of the United States, residing at Chicago, in the county of Cook, State of Illinois, have invented certain new and useful Improvements in Sewing-Machines, of which the following is a description, reference being had to the accompanying drawing, and to the letters and figures of reference marked thereon.

The invention relates to new and useful improvements in sewing machines, and more especially the presser foot for a sewing machine.

An object of the invention is to provide a presser foot which will properly coöperate with a feeding mechanism, wherein said feeding mechanism has an auxiliary part located at one side of and in advance of the stitching mechanism.

A further object of the invention is to provide a presser foot with yielding side members, one of which yields vertically, while the other yields vertically and also rocks about an axis.

These and other objects will in part be obvious, and will in part be hereinafter more fully described.

In the drawings, which show by way of illustration, one embodiment of the invention,—Figure 1 is a front elevation of a machine with my improved presser foot thereon, certain of the parts being in section; Fig. 2 is a top plan view with the work plate removed, and showing in dotted lines the position of the presser foot; Fig. 3 is a side view of the presser foot, showing in detail the position of the auxiliary part of the feed dog relative to the presser foot; Fig. 4 is a sectional view, showing the vertically yielding part; Fig. 5 is a top plan view of the presser foot; Fig. 6 is a bottom view of the same; Fig. 7 is a section centrally through the presser foot; Fig. 8 is a section showing the vertically yielding and oscillating part.

The sewing machine, as herein shown, consists of a bed plate 1, an overhanging arm 2 on which is mounted a needle lever 3, which is oscillated by a link 4 from the main shaft. Said needle lever reciprocates a needle bar 5, which carries, as herein shown, three needles 6. A looper 7 beneath the work support 8 coöperates with all three needles. Thread-laying fingers 9 and 10 are

herein shown, which operate to lay a thread back and forth in front of the needles, so that said thread will be stitched to a fabric.

The feeding mechanism in the present illustration of the invention, includes a feed bar 11, carrying a main feed dog 12. Said feed bar is reciprocated back and forth by means of a link 13, which is connected to a crank on the end of the main shaft 14. The main feed bar 11 carries an auxiliary feed dog 15, which moves back and forth with the main feed bar 11, and is given a differential movement from the main shaft 14. The above parts are all shown and described in the patent to Durand, No. 901,792, October 20th, 1908, and form no part of the present invention. It will be seen that the auxiliary feed dog is located at one side of, and in advance of the stitching mechanism.

My invention resides in a presser foot which will properly coöperate with a main feed dog and an auxiliary feed dog located as above noted. The presser foot, as herein shown, consists of the shank 16, which is secured to the lower end of the usual presser bar, which is yieldingly held depressed, and which may be raised when desired, by means of the usual cam lever or knee shift. The shank of the presser foot 16 carries a rigid central portion 17 (see Fig. 7). Said central portion is cut away as at 18 to form the needle slot. Fingers 19 project into the needle slot 18 and serve in the usual way as a means over which the thread may be laid by the thread-laying fingers 9 and 10. The presser foot is provided on one side with an auxiliary part 20. The shank of the presser foot 16 is slotted to receive an upwardly projecting part 21, formed rigidly with the auxiliary part 20. A post 22 is rigidly mounted on the part 21, and slides in a suitable opening in the shank. The part 21 is cut away at 23, and a pin 24 carried by the shank 16 extends through the opening 23, and serves to limit the downward movement of the auxiliary part 20. The auxiliary part 20 is yieldingly pressed downwardly by a spring 25, which bears on the upper end of the post 22. The spring 25 is secured to the presser foot by means of a screw 26.

On the other side of the main portion 17 of the presser foot is an auxiliary presser part 27. Said presser part 27 fits in a slot formed in the shank 16, and carries an upwardly projecting post 28 which extends

through the opening 29 formed in the shank 16. The post 28 is of slightly smaller diameter than the width of the opening 29, so that said post can rock or tilt slightly in the opening. The auxiliary part 27 also has an opening 30 which receives a stop pin 31, carried by the shank 16 of the presser foot. This opening 31 serves to limit the downward movement of the auxiliary part 27. A 10 spring 32 which may be secured by the screw 28, extends forward of the shank 16 of the presser foot, and bears upon the upper surface of the auxiliary part 27, as shown in Figs. 3 and 5.

15 The forward end of the spring is deflect-
ed, as at 33, to give the same a better bearing
surface upon the auxiliary part. The spring
32 normally holds the forward end of the
auxiliary foot 27 thrown downward, so that
20 the post 28 engages the forward side of the
opening 29. Said spring will also hold the
entire auxiliary portion 27 forced down-
ward, so that the slot 30 engages the stop
pin 31. The slot 30 is so shaped that if
25 pressure is brought to bear directly under
the entire auxiliary foot 27, the whole part
will move bodily vertically against the ten-
sion of the spring 32.

If pressure is brought against the forward
30 end of the auxiliary foot 27, it will raise the
forward end. The post 28 will tilt in the
slot 29, and the slot 30 will allow the auxil-
iary part 27 to swing about an axis. My
improved foot is so located relative to the
35 feeding mechanism herein shown, that the
auxiliary part 27 extends over and coöper-
ates with the auxiliary feed dog 15, while
the main part of the presser foot and the
auxiliary part 20 will coöperate with the
40 main feed.

Both the auxiliary parts 20 and 27 extend
slightly beneath the lower surface of the
main portion 17, (see Fig. 7). The pur-
45 pose of this is to allow the auxiliary parts
to have an independent downward yielding
movement, so that they can move below the
lower surface of the main foot and properly
guide and direct the fabric to the stitching
50 mechanism. The threads which are led back
and forth in front of the stitching mecha-
nism, are engaged solely by the main part
of the presser foot.

While I have shown my presser foot as
applied to a sewing machine having a differ-

ential feeding mechanism, it is obvious that 55
the presser foot may be used in other ma-
chines, and in connection with a feeding
mechanism of a different character, if so
desired.

I do not herein claim the combination of 60
the presser foot with differential feeding
mechanism as that is claimed in my appli-
cation (a division of this) filed the 4th day
of April, 1914, Serial No. 829,498.

Having thus described my invention, what 65
I claim as new and desire to secure by Let-
ters Patent, is:

1. A presser foot including in combina-
tion, a main portion, an auxiliary portion
located on one side thereof, means for sup- 70
porting said auxiliary portion, so that it
may yield vertically bodily and have a piv-
otal movement also, a second auxiliary por-
tion located on the other side of said main
portion, and means for supporting said sec- 75
ond auxiliary portion so that it may yield
vertically bodily.

2. A presser foot including in combina-
tion, a main portion, an auxiliary portion
having a post sliding in a suitable opening 80
in the presser foot shank, and having a hori-
zontal opening with a pin carried by the
shank fitting in said opening, and limiting
the downward movement of the auxiliary
part, and a spring bearing upon said post 85
to keep the auxiliary portion or foot, nor-
mally depressed, said stop pin also serving
as a pivot for said auxiliary portion.

3. A presser foot including in combina-
tion, a main portion, an auxiliary portion 90
having a post sliding in a suitable opening
in the presser foot shank, and having a hori-
zontal opening with a pin carried by the
shank fitting in said opening, and limiting
the downward movement of the auxiliary 95
part, and a spring bearing upon said post
to keep the auxiliary portion or foot
normally depressed, said stop pin also serv-
ing as a pivot for said auxiliary portion,
and a second auxiliary portion having a 100
bodily vertical movement.

In testimony whereof I affix my signature,
in presence of two witnesses.

RUSSEL G. WOODWARD.
